UNITED STATES PATENT OFFICE.

WILLIAM H. HALL, OF TIFFIN, OHIO.

CONNECTING-ROD FOR BRICK-MACHINES.

SPECIFICATION forming part of Letters Patent No. 448,231, dated March 17, 1891.

Application filed January 11, 1890. Serial No. 336,685. (No model.)

To all whom it may concern:

Be it known that I, WILLIAM H. HALL, a citizen of the United States, residing at Tiffin, in the county of Seneca and State of Ohio, 5 have invented a new and useful Improvement in Connecting-Rods, of which the following is a specification.

My invention relates to that class of connecting-rods or pitmen employed for pressing the bricks in brick-machines and for analogous purposes in other mechanism; and it consists, first, in improved means for adjusting the length of the pitman, and, second, in an improved construction by which the pitman may yield to excessive strains.

I have illustrated my invention as applied to the pitman of a brick-machine.

In the drawings, Figure 1 is a front elevation of a brick-machine provided with one of 20 my improved pitmen. Fig. 2 is a rear elevation of the pitman. Fig. 3 is a longitudinal section of the same, and Fig. 4 is a perspective view of the same.

A represents the frame of a brick-machine; 25 B, a press-box; C, a plunger, and D a connecting-rod or pitman operated by a crank-arm E, mounted on an actuating-shaft or other suitable means. The connecting-rod is provided at one end with a box f, having a bearing f', 30 to which the crank-arm E is journaled. The box f is adapted to slide in a slot in the connecting-rod D and to be guided on the walls d d of the slot. To this box is hinged a link h, which is jointed at its other end to a second link h', which in turn is hinged to a rigid part of the pitman. A set-screw i takes through 35 a cross-piece j, connecting the slot-walls nearly over the middle link-joint. By this set-screw the middle joint may be forced out of line 40 with the two end link-joints and against the resistance of a spring k. The tension of this spring is regulated by a set-screw l, taking through one of the links. It is obvious that if the plunger meets with an excessive resistance, such as would be occasioned by the 45 interposition of a foreign substance, like a stone or piece of iron, the crank-arm continuing its motion will cause the box f to slide in the slot in the connecting-rod D and force the middle 50 link-joint, which is set out of line with the two end joints, still farther out of line, against the resistance of the spring, thus relieving the

pitman and its connections from the strain that otherwise might break or damage the machine. As soon as the excessive strain is relieved the spring will force the middle link-joint into its normal position. By adjusting the angle of the links by means of the set-screw i and the tension of the spring the amount of strain to which the pitman will 60 yield may be regulated. By making the combined length of the links in the yielding rod slightly longer than the slot the adjusting-screw i may be dispensed with; but I prefer to provide adjusting devices for both the 65 links and the spring.

The connecting-rod is provided with a bearing d', into which a wheel o is adapted to take, the points of contact of the wheel with the bearing being equidistant from the center of 70 the former. The periphery of the wheel o is provided with suitable gear o', into which a worm m meshes, the worm being operated by a hand-wheel n. The wheel o is also provided with an eccentric bearing p, to which the 75 plunger C may be coupled. Turning the hand-wheel n rotates the wheel o, raising or lowering the eccentric bearing, thereby lengthening or shortening the distance between it and the bearing f' in the box f, to which the crank-arm E is journaled, in effect lengthening or 80 shortening the connecting-rod. This construction permits of a very delicate adjustment, which may be made quickly and readily without disconnecting any parts, and one 85 which will lock itself against disturbance from any other source than the hand-wheel.

I claim—

1. The combination, in a yielding pitman, of a connecting-rod, a box adapted to slide 90 therein, two or more jointed links, one end of the series hinged to said box and the other hinged to the connecting-rod, and a spring resisting outward movement of the joints connecting the links, substantially as and for the 95 purpose specified.

2. The combination, in a yielding pitman, of the box f, sliding in a slot in the connecting-rod D, link h, jointed to said sliding box, a second link h', jointed to link h at one end 100 and at its other hinged to the connecting-rod, set-screw i, spring k, and set-screw l, substantially as and for the purpose specified.

3. The combination, in a pitman, of a bear-

ing at each end thereof, a wheel taking into one of the bearings and capable of being rotated therein, the points of contact of the wheel with the bearing being equidistant from its center, an eccentric bearing for the wheel, and a worm and worm-wheel for turning the latter, combined and operating to lengthen or shorten the distance between the

eccentric bearing at one end of the pitman and the bearing at the other end thereof, substantially as and for the purpose specified.
